UNITED STATES PATENT OFFICE.

GUSTAV B. PETSCHÉ, OF PHILADELPHIA, PENNSYLVANIA, ASSIGNOR TO SOUTHWARK FOUNDRY AND MACHINE COMPANY, OF PHILADELPHIA, PENNSYLVANIA, A CORPORATION OF PENNSYLVANIA.

BLOWING-ENGINE OR COMPRESSOR.

No. 894,048.

Specification of Letters Patent.

Patented July 21, 1908.

Application filed August 4, 1906. Serial No. 329,177.

To all whom it may concern:

Be it known that I, GUSTAV B. PETSCHÉ, a subject of the Emperor of Germany, residing in the city and county of Philadelphia, in the 5 State of Pennsylvania, have invented a certain new and useful Improvement in Blowing-Engines or Compressors, of which the following is a true and exact description, reference being had to the accompanying 10 drawings, which form a part thereof.

My invention relates to blowing engines or compressors and has for its object to provide an engine of this kind having circumferentially arranged admission ports extending 15 through the walls of the cylinder at each end thereof and the sliding gridiron delivery valves working on the heads of the cylinder; my invention also comprising other detailed features of construction, all of which will be 20 best understood as described in connection with the drawings in which they are illustrated and in which

Figure 1 is a side elevation of an engine embodying my invention. Fig. 2 a plan view 25 thereof. Fig. 3 an end view with the man-hole plates, indicated at G, G, removed, and the delivery valves broken away from their actuating rods. Fig. 4 is a longitudinal section on the line 4—4 of Fig. 3, and Fig. 5, a 30 section through one of the auxiliary cylinders taken as on the line 5—5 of Fig. 3.

A indicates the end of the actuating engine which may be of any usual or convenient 35 construction; B, B, extensions of the engine framing which connect it with the compressing cylinder.

C, is a crosshead guide. D, D, portions of the base supporting the fixed cylinder heads indicated at E, E, said heads, as shown, being made up of the cylinder heads proper, indicated at E'; the cylindrical portions E², which serve as bearings for a reciprocating cylinder body to be described, the head portions E' being formed with grid iron ports 45 indicated at E³, E³, located on opposite sides of the center of the engine and having valve seats indicated at E⁴ formed on the outer side of the head E'. From the heads E' extend the hollow hubs E⁵ the outer ends of 50 which connect with the casing E⁶ between which and the heads E' are formed the receiving chambers F, F.

E', E', indicate openings in the casing E⁶, normally closed by the plates G, G.

F' indicates a common receiving chamber 55 connecting the chambers F, F.

H, is the movable cylinder body supported and moving on the cylindrical portions E², E², of the heads and having at each end a series of circumferentially arranged admission ports H'. The cylinder body, as shown, is also provided with a central circumferential groove indicated at H².

I is a bearing shaft supported above the cylinder and supporting at its ends, the 65 U-shaped yoke I' having a bearing pin I² at its lower end to which is connected the actuating rod J. The arms of the yoke support the bearing pins I³, I³, which project into the groove H² and support friction rolls I⁴, I⁴, 70 which fit in said groove H².

The rod J connects with the lever arm J' on the rock shaft J² which is actuated through lever arm J' and rod J⁸ by some constantly moving part of the engine not shown. 75 There is also attached to the rock shaft the lever arm J³, which communicates motion through rod J⁴, the double armed rock lever J⁵, and the rock lever J⁶, to the rod N.

K, is the piston rod, K' the piston working 80 in the cylinder, K² a crosshead supported on the bearing C. L, L, etc., are sliding delivery valves moving on the bearings E⁴ to open and close the ports E³, E³. The upper valve L of each cylinder head has its stem or valve 85 rod R connected with the piston Q working in the auxiliary cylinder P and having attached or connected to it the dash pot piston Q' working in the extension P' of cylinder P, as shown. Laterally extending bearing pins 90 Q³ connected with each piston Q, as shown in Fig. 5, are pivotally connected to the upper forked end of a rock lever S which is fulcrumed on the engine casing midway between the stem R and the stem R' of the corresponding lower delivery valve L. The stem R' is pivotally connected to the lower end of the rock lever S. In consequence of this arrangement the two delivery valves on each cylinder head move in opposite directions to 100 open or to close.

P², indicates a passage through the auxiliary cylinder casting and supporting the cam O, two of such cams being attached to each rod N in connection with the auxiliary cylinders arranged at each end of the compressing cylinders.

T, T, are conduits connecting with the

auxiliary cylinders P and connecting, as shown, through flexible pipes T², with the interior of the cylinder H; T', T', are valve boxes of the usual kind employed in such connections.

In operation the piston is moved back and forth in the compressing cylinder and at the same time the oscillations given to the yoke I' cause the cylinder body H to reciprocate in such manner as to alternately open the circumferential admission ports H', H', at its ends. A relatively uniform motion is given to the sliding cams O, O, which are arranged so as to act upon the cam rollers Q² and move the pistons Q into the bottom of the auxiliary cylinders P and thus move the delivery valves in a direction to close the delivery ports E³, E³, immediately in advance of the beginning of the motion of the piston K' away from said ports. Immediately after closing the ports the high portions O' of cams O move out from under the cam rollers Q² leaving the pistons Q' free to open and they do open when the pressure entering the auxiliary cylinders through the conduit connéctions T² become sufficiently high to overcome the frictional pressure holding the delivery valves to their seats.

It will be seen that the structure claimed herein provides in a simple and effective manner ample port space for both admission and delivery and retains all features of rapid and well timed movement of the valves which characterize the best features of modern blowing engines.

Certain features of construction and arrangement shown and described but not broadly claimed herein are broadly claimed in my copending application, Serial No. 329,176, filed of even date herewith.

Having now described my invention, what I claim as new and desire to secure by Letters Patent is

1. In a blowing engine or compressor,

stationary cylinder heads having receivers 45 inclosing their outer ends and delivery ports formed through them in combination with a longitudinally reciprocating cylinder body fitting on said heads, circumferential admission ports situated at both ends of the cylinder and opened and closed by the movements of the cylinder body, sliding gridiron delivery valves moving on the outer faces of the heads, means for closing the delivery valves moving in fixed relation to the movements of the cylinder body and independent means for opening said valves.

2. In a blowing engine or compressor, stationary cylinder heads having receivers 60 inclosing their outer ends and two sets of delivery ports formed through them, one set on each side of the center of the head, in combination with a longitudinally reciprocating cylinder body fitting on said heads, circumferential admission ports situated at both 65 ends of the cylinder and opened and closed by the movements of the cylinder body, two sliding gridiron delivery valves moving on the outer faces of each of the heads and so placed and connected that they move in opposite 70 directions to open and close their delivery ports, means for closing the delivery valves moving in fixed relation to the movements of the cylinder body, and independent means for opening said valves.

3. In a blowing engine or compressor, the combination of stationary cylinder heads, a longitudinally reciprocating cylinder body having a circumferential groove formed around it, a yoke pivoted at one side of the 80 cylinder, means for oscillating said yoke and slides secured to the side of the yoke and fitting in the groove of the cylinder whereby the cylinder is reciprocated.

GUSTAV B. PETSCHE.
